SHEET FEEDING APPARATUS

Glen E. Wimmer, Chicago, Ill., assignor to Ditto,
Incorporated, Chicago, Ill., a corporation of
West Virginia

Application May 13, 1939, Serial No. 273,373

16 Claims. (Cl. 271—39)

This invention relates to sheet feeding apparatus of the type by which a single sheet may be fed from a pile of sheets on a table by a roller or rollers rotatably mounted on an arm extending over the table and movable vertically so as to permit the roller means to press against the top sheet of the pile, means being provided for driving the roller at timed intervals in the direction for causing the top sheet of the pile to move 5 edgewise forwardly from the pile. It is the object of the invention to provide an improved form and arrangement of parts by which the downward pressure of the roller on the pile of sheets may be adjusted and controlled for enabling the 10 roller to work satisfactorily with sheets of different thickness, weight, hardness, and smoothness, so as to insure that a single sheet shall be moved at each period of rotation of the roller.

In my improved arrangement, I have provided 15 a spring which tends when in tightened condition to apply a downward pressure on the arm which carries the forwarding roller or rollers, means being provided for adjusting the effective strength of such spring so as to cause the roller means to press with the desired degree of force 20 on the pile of sheets. My improved construction also comprises an improved arrangement of latching means for holding the arm and the connected shaft in turned position for supporting the 25 forwarding rollers in spaced relation to the pile of sheets so as to enable the operator easily to renew the pile of sheets on the table. My improved arrangement is such that, when the operator desires to lower the rollers from their elevated position again into their lowered position 30 for engagement with the pile of sheets, he can bring about a release of the latching means by an upward movement of the roller a short distance beyond the position at which they are normally held, and such that, upon the next succeeding 35 upward movement of the rollers after being lowered into engagement with the pile and without any attention on the part of the operator, the latching means again is in condition to be effective for holding the rollers in their elevated position.

It is another object of my invention to improve apparatus of this type in sundry details hereinafter pointed out. The preferred means by 40 which I have accomplished my several objects are illustrated in the accompanying drawings, in which—

Fig. 1 is a side view of a duplicating machine equipped with my improved sheet forwarding apparatus;

Fig. 2 is a top plan view of a portion of the machine as shown in Fig. 1;

Fig. 3 is a vertical sectional view taken substantially at the line 3—3 of Fig. 1;

Fig. 4 is a vertical sectional view taken substantially at the line 4—4 of Fig. 2;

Fig. 5 is a vertical sectional view taken substantially at the line 5—5 of Fig. 4;

Fig. 6 is a vertical sectional view taken substantially at the line 6—6 of Fig. 2;

Fig. 7 is an enlarged detail view similar to a portion of Fig. 3;

Fig. 8 is a vertical sectional view taken substantially at the line 8—8 of Fig. 7;

Fig. 9 is a vertical sectional view taken substantially at the line 9—9 of Fig. 8;

Figs. 10 and 11 are perspective views of operating parts of the structure as shown in Fig. 9;

Figs. 12, 13 and 14 are vertical sectional views taken substantially at the line 12—12, the line 13—13, and the line 14—14, respectively, of Fig. 9;

Fig. 15 is a view similar to a portion of Fig. 1 but on an enlarged scale with certain of the parts shown in section and showing some of the parts in changed position;

Fig. 16 is a view similar to Fig. 15 but showing a second changed position of the parts;

Fig. 17 is a view generally similar to a portion of the mechanism as shown in Figs. 15 and 16, but with the section taken at a different point and showing a third changed position of the parts; and

Fig. 18 is a view similar to Fig. 17 but showing the forwarding rollers in the same position as in Fig. 1.

Referring now to the several figures of the drawings, in which corresponding parts are indicated by the same reference characters, 25 and 26 indicate standards at opposite sides of the machine, as is clearly shown in Fig. 2, each of said standards being in the form of a housing pressed out of sheet metal. Said housings 25 and 26 are connected in rigid relation to each other by a considerable number of parts, including an angle bar 27, as is best shown in Fig. 1. Between the standards 25 and 26, I have mounted a drum 28 supported by a shaft 29 which is driven, in the arrangement shown, by a handle 30, as is clearly shown in Figs. 2 and 3. As is clearly shown in Fig. 1, the drum 28 is provided with gripper means 31 adapted to hold a master sheet 32 releasably in position upon the drum in a manner fully understood in connection with machines of this type. A platen roller 33 is rotatably mounted below the drum in position to apply pressure 55

against the master sheet 32. Forwarding rollers 34 and 35 are provided at a short distance from the drum 28, a moistening mechanism 36 of any suitable type being provided for applying a film of solvent to a copy sheet moving forward between the rollers 34 and 35, the roller 34 being driven by any suitable means not shown. In the arrangement shown, the roller 35 is carried by a pivotally mounted arm 37 to the forward end of which a coiled spring 38 is connected for pressing the roller 35 toward the roller 34. A receptacle 39 for solvent is provided in which there is located a pump 40 for delivering solvent through a pipe 41 to the moistener mechanism 36. A drain pipe 42 is provided between the moistening mechanism 36 and the receptacle 39 for returning surplus solvent to said receptacle. The pump 40 is operated by a lever 43 which in turn is reciprocated by a lever 44 provided with a roller 45 at its end portion in position to engage a cam 46 carried by the shaft 29. The arrangement is such that upon each revolution of the drum 28 the pump 40 is given an operative stroke for forcing a supply of solvent into the moistening mechanism 36.

25 Adjacent to the drum 28, I have provided a table 47 which is preferably removable from its position, being removably secured in the arrangement as shown in Fig. 1 by a latch arm 48. The table is provided with side margin bars 49 which are pressed downwardly upon the table by means comprising coiled springs 50, as shown in Fig. 3, the margin bars 49 being adjustable sidewise for holding a pile of copy sheets 51 in the desired adjusted position on the table, as shown in said Fig. 3. At the edge of the table disposed toward the drum 28, guide plates 52 and 53 are provided in forwardly converging position with respect to each other so as to direct a sheet 51 to the bite of the rollers 34 and 35 (see Fig. 1).

40 The means for feeding copy sheets from the pile 51 to the rollers 34 and 35 comprises an arm 54 pivotally mounted above the table 47 so as to be movable vertically toward and from the table. Upon its forward end, the arm 54 is provided with a transversely extending shaft 55 upon which are mounted paper feeding rollers 56 which in their lowered position are adapted to engage the top face of the top sheet of the pile on the table 47.

50 In the arrangement shown, the arm 54 is in the form of a housing which is fixedly mounted upon the inner end of a tubular shaft member 57 extending over the table from one side of the machine, as is best shown in Fig. 3. At its outer end, the tubular shaft member 57 is releasably connected with a spindle 58 (see Fig. 9) which is journaled in a bearing block 59 carried by the framework of the machine. In the arrangement shown, the frame of the machine is provided with auxiliary standard members 60 and 61 at opposite sides of the machine for supporting the members upon which the arm 54 is mounted, the bearing block 59 being fixedly mounted in the auxiliary standard 61. The tubular shaft member 57 is releasably connected with the spindle 58 by means of a socket member 62 in an opening in the outer end of which a head 63 carried by the spindle 58 is mounted, pins 64 carried by the head being arranged in engagement with notches 65 in the side wall portions of the socket member for causing the tubular shaft member 57 and the spindle 58 to rotate together.

70 The tubular shaft member 57 is reinforced in

position by a shaft member 66 which is journaled at an intermediate point in the housing 54 and extends from such bearing into the tubular shaft member and into engagement with a bearing 67 carried by the socket member 62. At the 5 opposite side of the machine (at the left in Fig. 3), the shaft 66 extends into a sleeve member 68 which is slidable longitudinally of the shaft 66 so as to be adapted to have releasable engagement with a short shaft section 69 arranged in alignment with the shaft 66. In the arrangement shown, the shaft section 69 is provided with a transversely positioned pin 70 adapted to engage notches 71 in the end of the sleeve 68 so as to cause the shaft 66 to rotate 10 with the shaft section 69. A coiled spring 72 interposed between the end of the shaft 66 and a pin 73 extending across the sleeve member 68 serves normally to hold the sleeve member pressed to the limit of its motion toward the 20 left in Fig. 3 for maintaining an operative connection between the shaft 66 and the shaft section 69. A pin 74 carried by the sleeve 68 and engaging a longitudinally extending slot 75 in the shaft 66 causes the shaft 66 to rotate with 25 the sleeve while at the same time permitting longitudinal movement of the sleeve against the action of the spring 72 when the operator desires to remove from the machine the arm 54 and its supporting parts as above described. 30

The shaft 55 and the paper feeding rollers 56 are connected with the shaft 66 so as to be driven thereby through the medium of sprocket gears 76 and 77 and a cooperating sprocket chain 78, as is clearly shown in Fig. 6. The 35 shaft section 69 is driven in counter clockwise direction in Fig. 1, for causing the rollers 56 to move in counter clockwise direction for carrying a sheet 51 toward the right in said figure, by means of a clutch member comprising a head 79 carried by a pinion 80 journaled upon said shaft section 69, such head member being provided with notches 81 in its face in which balls or rollers 82 are mounted for driving a heavy plate 83 connected with the shaft section 69. 45 The arrangement is such that when the head 79 is driven in clockwise direction in Fig. 5 the clutching members 82 serve to drive the heavy plate 83 in the same direction for giving the rollers 56 the desired counter clockwise rotation in said Fig. 1. 50

For driving the head 79 and the pinion 80 in clockwise direction in Fig. 5 (in counter clockwise direction in Fig. 1), I have provided a lever 84 pivotally mounted at an intermediate point upon the framework of the machine, such lever being provided with teeth 85 on its upper end meshing with the pinion 80. At its lower end, the lever 84 is connected with one end of a link 86, the opposite end of which is pivotally connected with a lever 87 pivotally mounted at 60 88 upon the framework of the machine and provided with a roller 89 rotatably mounted upon its upper end. The roller 89 is actuated by the cam 46 for oscillating the lever 84, a spring 90 being connected with the link 86 for holding the roller 89 in engagement with the cam 46. The arrangement is such that upon each revolution of the drum 28 the spring 90 draws the link 86 toward the right in Fig. 1 for causing rotary movement of the pinion 80 in clockwise direction in said figure and that at another point in the revolution of the drum the cam 46 forces the roller 89 toward the right for carrying the link 86 toward the left in said Fig. 1 against the 70 75 80 85 90 95

action of the spring 90 for causing rotation of the pinion 80 in the opposite direction. Upon the rotation of the pinion 80 in one direction the rollers 56 are driven for forwarding a copy sheet; upon rotation of the pinion in the opposite direction the free-wheeling clutch yields for permitting the rollers 56 to remain stationary. After a sheet has been moved by the rollers 56 into operative engagement with the forwarding rollers 34 and 35, the free-wheeling clutch permits the sheet to continue its movement toward the right independently of the pinion 80.

Referring now to Fig. 9, where the arrangement is best shown, 91 indicates a member in the form of a disk which is fixedly mounted upon the spindle 58, to which one end of a coiled spring 92 is connected, the opposite end of said spring being connected to the end wall of a housing 93 in the form of a drum closed at its outer end. At its inner end, the drum 93 is provided with a plurality of sockets 94 spaced thereabout in position to enable a selected one of said sockets to engage a pin 95 carried by the standard member 61 near its upper end. The arrangement is such that the drum 93 may be moved outwardly against the action of the spring 92 for withdrawing the drum from engagement with the pin 95, whereupon the drum can be given a rotary movement for either tightening or loosening the spring 92, after which the drum can be again moved toward the left for bringing one of the sockets 94 again into engagement with the pin for maintaining the spring 92 in the changed stressed condition. As will be appreciated from an inspection of Fig. 18, for example, when the spring 92 has been put under tension by rotary movement of the drum 93 in clockwise direction in said figure, the spring serves through the pinion 58 and the tubular shaft 57 to apply downward pressure upon the arm 54 and the rollers 56 for holding the rollers pressed downwardly with the desired tension. For limiting the outward movement of the drum 93, I have provided a machine screw 93a whose head engages a flange 93b about the drum at its inner end.

The disk 91 is also arranged to have a latching effect for holding the arm 54 and the rollers 56 in elevated position above the table as shown in Fig. 15. For effecting this result, the disk 91 is cut away at one side to provide a shoulder 96 (see Fig. 11) which is adapted in one position of the disk to engage a dog 97 pivotally mounted in a pocket 98 in the bearing member 59, as is clearly shown in Fig. 9. The arrangement of the parts is such that when the arm 54 is in lowered position the shoulder 96 is at one side of the disk 91, as is shown in Fig. 18, but that when the arm 54 is raised the shoulder moves into position as shown in Fig. 15 for permitting the dog 97 to move downwardly into operative engagement with the shoulder, as shown in said Fig. 15. The dog 97 of course serves to hold the arm 54 and the rollers 56 in elevated position.

Between the disk 91 and the bearing member 59, I have provided a bearer 99, also in the form of a disk, loosely mounted upon the spindle 58 and cut away at one side to provide a shoulder 100 corresponding substantially to the shoulder 96 of the disk 91. Means is provided for causing the disks 91 and 99 to rotate together with a limited amount of lost motion between them, such means comprising a pin 101 projecting from the disk 91 so as to extend through a circumferentially elongated opening 102 in the bearer disk 99.

For controlling the movement of the disk 99, I have provided a bowed spring 103 mounted on the outer face of the bearing member 59 having a shoulder 104 at about its middle portion adapted to engage alternatively a narrow groove 105 or a circumferentially elongated groove 106 in the face of the disk (see Fig. 10). The spring 103 and the grooves or notches 105 and 106 are so arranged that the shoulder 104 of the spring engages the circumferentially elongated notch 106 when the arm 54 is in either its lowered position as shown in Fig. 18 or in its normal elevated position as shown in Fig. 15. When the arm 54 reaches the position as shown in Fig. 15, the dog 97 engages the shoulder 96 for holding the arm in its raised position and the pin 101 is brought into engagement with the opposite end of the opening 102 from that at which it is shown in Fig. 18. Upon further upward movement of the arm 54, the pin 101 causes the bearer 20 disk 99 to rotate in counterclockwise direction in said Fig. 15 with the disk 91, serving to force the shoulder 104 of the spring 103 out of engagement with the elongated notch 106 and into engagement with the notch or groove 105 into 25 the position as shown in Fig. 16. As the bearer disk 99 approaches the position as shown in Fig. 16, the dog 97 is forced upwardly by a camming action so as to be relieved from the shoulder 96 of the disk 91. Under such circumstances, the 30 arm 54 is then free to move in clockwise direction from the position shown in Fig. 16 to the position shown in Fig. 18. In the course of such movement, the pin 101 is brought into engagement with the end of the elongated opening 102 at the 35 left as shown in Fig. 17 after the shoulder 96 of the disk 91 has passed the dog 97. Upon the continued rotation of the disk 91 in clockwise direction from the position as shown in Fig. 17, the shoulder 104 of the spring is forced out of engagement with the groove 105 and again into engagement with the elongated groove or notch 106 into the position as shown in Fig. 18.

As is clearly shown in Fig. 15, a pin 107 carried by the bearing member 59 serves by engagement with the elongated notch 106 to limit the rotary movement of the bearer disk 99. In the arrangement shown, a pin 108 is provided on the drum 93 in position to engage the dog 97 for limiting the rotary movement of said drum 93 in either direction.

By the use of my improved construction, the latching mechanism comprising the disk 91 and the dog 97 is effective when the arm 54 is raised to hold the arm against downward movement. When however the arm is raised to a higher point above the table 41, the bearer 99 is brought into changed position so as to cause the dog 97 to be released from the shoulder 96 and to be maintained in raised position upon a subsequent downward movement of the arm 54 until the shoulder 96 of the latching disk 91 has passed the dog 97.

By my improved construction, I have provided a mechanism by which the strength of the pressure of the sheet feeding rollers upon the pile of sheets can be regulated to meet varying requirements when different types of paper are employed. In connection with this arrangement, I have provided an automatically acting latch mechanism adapted to hold the arm in elevated 70 position as desired and adapted upon an easy manipulation of the parts to release for permitting downward movement of the arm when desired.

While I prefer to employ the form and arrange- 75

ment of parts as shown in my drawings and as above described, it is to be understood that my invention is not limited to the construction and arrangement as shown except so far as the claims may be so limited, it being understood that changes might well be made in the structure without departing from my invention.

I claim:

1. In a sheet feeding apparatus, the combination of a frame, a table mounted on said frame so as to support a pile of sheets, a rock shaft rotatably mounted adjacent to said table, an arm mounted on said rock shaft so as to move therewith and extending over said table, paper feeding means carried by said arm adapted by engagement with the top sheet of the pile to move said top sheet edgewise from the pile, and yielding means mounted on said frame and releasably bearing on said rock shaft for pressing said paper feeding means downwardly and adjustable for controlling the degree of pressure of said paper feeding means on said sheet.
2. In a sheet feeding apparatus, the combination of a frame, a table mounted on said frame so as to support a pile of sheets, a rock shaft rotatably mounted on said frame so as to extend over the table and so as to be readily removable from operative position, an arm mounted on said rock shaft so as to move toward and from said pile of sheets as the shaft is rotated, roller means rotatably mounted on said arm in position to engage the top face of the top sheet of said pile, means for driving said roller means intermittently in the direction for causing said roller means to move said top sheet edgewise from the pile, and yielding means mounted on said frame and detachably connected with said rock shaft for pressing said roller means downwardly and adjustable for controlling the degree of pressure of said roller means on said top sheet.
3. In a sheet feeding apparatus, the combination of a frame, a table mounted on said frame so as to support a pile of sheets, a rock shaft rotatably mounted on said frame so as to extend over the table and so as to be readily removable from operative position, an arm mounted on said rock shaft so as to move toward and from said pile of sheets as the shaft is rotated, roller means rotatably mounted on said arm in position to engage the top face of the top sheet of said pile, means comprising a second shaft serving as a support for said first-named shaft and as driving means for intermittently rotating said roller means in the direction for moving the top sheet from the table, and yielding means mounted on said frame and detachably connected with said rock shaft for pressing said roller means downwardly and adjustable for controlling the degree of pressure of said roller means on said top sheet.
4. In a sheet feeding apparatus, the combination of a frame, a table mounted on said frame so as to support a pile of sheets, a tubular rock shaft rotatably mounted on said frame at one side of said table and extending over the table, a second shaft member rotatably mounted on said frame at the opposite side of the table and extending into said tubular shaft member, an arm mounted on said tubular rock shaft so as to move therewith above said table, roller means rotatably mounted on said arm in position to engage the top face of the top sheet of said pile, means for driving said roller means from said second shaft, means for driving said second shaft intermittently in the direction for causing said roller means to move said top sheet edgewise from the

pile, and yielding means bearing on said rock shaft for pressing said roller means downwardly and adjustable for controlling the degree of pressure of said roller means on said top sheet.

5. In a sheet feeding apparatus, the combination of a frame, a table mounted on said frame so as to support a pile of sheets, a spindle rotatably mounted on said frame at one side of said table, a tubular rock shaft releasably connected with said spindle so as to rotate therewith when in position, a second shaft rotatably mounted on said frame at the opposite side of the table and extending into said tubular shaft member and mounted so as to be removable from operative position with said tubular shaft member, an arm mounted on said rock shaft so as to move therewith above said table, roller means rotatably mounted on said arm in position to engage the top face of the top sheet of said pile, means for driving said roller means from said second shaft, means for driving said second shaft intermittently in the direction for causing said roller means to move said top sheet edgewise from the pile, and yielding means bearing on said spindle for applying downward pressure through said tubular shaft member and arm on said roller means and adjustable for controlling the degree of such downward pressure.

6. In a sheet feeding apparatus, the combination of a frame, a table mounted on said frame so as to support a pile of sheets, a spindle rotatably mounted on said frame at one side of said table, a tubular rock shaft releasably connected with said spindle so as to rotate therewith when in position, a second shaft rotatably mounted on said frame at the opposite side of the table and extending into said tubular shaft member and mounted so as to be removable from operative position with said tubular shaft member, an arm mounted on said rock shaft so as to move therewith above said table, roller means rotatably mounted on said arm in position to engage the top face of the top sheet of said pile, means for driving said roller means from said second shaft, means for driving said second shaft intermittently in the direction for causing said roller means to move said top sheet edgewise from the pile, a coiled spring about said spindle having one end secured fixedly to the spindle, a housing member about the spindle to which the opposite end portion of said spring is attached, and means for holding said housing in adjusted position with respect to said frame for adjusting the effective strength of said spring.

7. In a sheet feeding apparatus, the combination of a frame, a table mounted on said frame so as to support a pile of sheets, a spindle rotatably mounted on said frame at one side of said table, a tubular rock shaft releasably connected with said spindle so as to rotate therewith when in position, a second shaft rotatably mounted on said frame at the opposite side of the table and extending into said tubular shaft member and mounted so as to be removable from operative position with said tubular shaft member, an arm mounted on said rock shaft so as to move therewith above said table, roller means rotatably mounted on said arm in position to engage the top face of the top sheet of said pile, means for driving said roller means from said second shaft, means for driving said second shaft intermittently in the direction for causing said roller means to move said top sheet edgewise from the pile, a coiled spring about said spindle having one end secured fixedly to the spindle, a housing

member in the form of a drum closed at its outer end rotatably mounted with respect to said spindle and having the opposite end portion of said spring fixedly connected to the housing, and 5 a pin carried by said frame opposite to the wall of said drum adapted to engage any of a plurality of sockets in said wall for holding said drum in adjusted position angularly with respect to the frame for controlling the effective strength 10 of said spring.

8. In a sheet feeding apparatus, the combination of a frame, a table mounted on said frame so as to support a pile of sheets, a shaft rotatably mounted on said frame, an arm mounted on said 15 shaft so as to move therewith toward and from said table, paper feeding means carried by said arm adapted by engagement with the top sheet of said pile to move said top sheet edgewise from the pile, and latch means adapted to act automatically when the arm is raised from its lowered operative position to hold the arm in raised position and adapted when the arm is raised still further to be released for permitting the arm again to descend to operative lowered position.

9. In a sheet feeding apparatus, the combination of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet of said pile to move said top sheet edgewise from the pile, and means comprising a dog and a shouldered latch member carried by said frame 25 and said shaft adapted by engagement when said arm is raised a short distance above the table to hold the arm in raised position and adapted when the arm is raised to a higher point to cause said dog to move out of engagement with 30 said latch member for permitting the arm to be lowered again to operative position.

10. In a sheet feeding apparatus, the combination of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet of said pile to move said top sheet edgewise from the pile, a pivotally mounted dog on said frame, a shouldered latch member carried by said shaft adapted at an intermediate point in an upward movement of said arm to engage said dog for holding the arm in raised position, and means actuated by a movement of said arm to the limit of its motion away from the table to hold said dog out of engagement with said shouldered latch member so as to permit said arm to descend to its lowered operative position.

11. In a sheet feeding apparatus, the combination of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet of said pile to move said top sheet edgewise from the pile, a pivotally mounted dog on said frame, a shouldered latch member carried by said shaft adapted at an intermediate point in an upward movement of said arm to engage said dog for holding the arm in raised position, a bearer rotatably mounted on said shaft adjacent to said latch member, lost motion connections between said latch member and said bearer

for causing the bearer to move in either direction with the latch member after the lost motion is taken up, and yielding means adapted to resist the movement of said bearer either into or out of the position at about the limit of its movement, said bearer being adapted at its said limit position at which it is yieldingly held to prevent said dog from engaging said latch member.

12. In a sheet feeding apparatus, the combination of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet of said pile to move said top sheet edgewise from the pile, a pivotally mounted dog on said frame, a shouldered latch member carried by said shaft adapted at an intermediate point in an upward movement of said arm to engage said dog for holding the arm in raised position, a bearer rotatably mounted on said shaft adjacent to said latch member, lost motion connections between said latch member and said bearer for causing the bearer to move in either direction with the latch member after the lost motion is taken up, and a spring carried by the frame adapted yieldingly to hold said bearer turned in the direction in which it is carried by a movement of said arm to the limit of its motion upwardly, said bearer being adapted in said position in which it is yieldingly held to prevent said dog from engaging said latch member.

13. In a sheet feeding apparatus, the combination of a frame, a table mounted on said frame so as to support a pile of sheets, a tubular rock shaft rotatably mounted on said frame at one side of said table and extending over the table, a second shaft rotatably mounted on said frame at the opposite side of the table and extending into said tubular shaft member, said two shaft members being readily removable from the frame by movement longitudinally with respect to each other, an arm mounted on one of said shaft members so as to move therewith toward and from said table, paper feeding means carried by said arm adapted by engagement with the top sheet of said pile to move said top sheet edgewise from the pile, and latch means connected with said frame and with the shaft member with which said arm is adapted to move adapted to act automatically when the arm is raised a short distance above the table to hold the arm in raised position and adapted when the arm is raised to a higher point to release for permitting the arm to be lowered again to operative position.

14. In a sheet feeding apparatus, the combination of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet of said pile to move said top sheet edgewise from the pile, a dog pivotally mounted on said frame so as to extend along the shaft directly above the shaft, a disk fixedly mounted on said shaft having a shoulder with which said dog may engage for holding the shaft in position to support the paper feeding means in upwardly spaced relation to said pile of sheets, and means comprising a second disk mounted on said shaft adapted by engagement with said dog when said arm is raised to a higher point above the table to move the dog out of engagement with said first-named

disk for permitting the arm to move again to its lowered operative position.

15. In a sheet feeding apparatus, the combination of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet 10 of said pile to move said top sheet edgewise from the pile, a dog pivotally mounted on said frame so as to extend along the shaft directly above the shaft, a disk fixedly mounted on said shaft having a shoulder with which said dog may engage for holding the shaft in position to support the paper feeding means in upwardly spaced relation to said pile of sheets, a second disk mounted in said shaft underneath said dog, and a pin on one of said disks extending into a circumferentially elongated opening in the other disk for causing one of said disks to move the other disk with a limited amount of lost motion between them, said second disk being adapted by engagement with said dog when said arm is raised to a higher point to move said dog out of engagement with said first-named disk for permitting said arm to move again to its lowered operative position.

16. In a sheet feeding apparatus, the combina-

tion of a frame, a table mounted on said frame so as to support a pile of sheets, a shaft rotatably mounted on said frame, an arm mounted on said shaft so as to move therewith toward and from said table, paper feeding means carried by said arm adapted by engagement with the top sheet of said pile to move said top sheet edgewise from the pile, a dog pivotally mounted on said frame so as to extend along the shaft directly above the shaft, a disk fixedly mounted on said shaft having a shoulder with which said dog may engage for holding the shaft in position to support the paper feeding means in upwardly spaced relation to said pile of sheets, a second disk mounted on said shaft underneath said dog, a pin on one of said disks extending into a circumferentially elongated opening in the other disk for causing one of said disks to move the other disk with a limited amount of lost motion between them, and yielding means adapted to resist the movement of said second disk either into or out of its limit position with respect to said first-named disk, said second disk being adapted by engagement with said dog when said arm is raised to a higher point to move said dog out of engagement with said first-named disk for permitting said arm to move again to its lowered operative position.
